FLAME HOLDER AND FUEL NOZZLE SUPPORTING MECHANISM FOR RAM JET ENGINES

Edwin P. Neikirk, Ferguson, and John Izo, Jr., Overland, Mo., assignors to McDonnell Aircraft Corporation, St. Louis, Mo., a corporation of Maryland

Application December 15, 1948, Serial No. 65,374

11 Claims. (Cl. 60—35.6)

1

This invention relates to ram jet engines and is more particularly directed to an improved flame holder, fuel nozzle arrangement, and support therefor.

The principal object of the invention is to produce a ram jet engine comprising a tubular member having a flame holder therein which will effectively direct a fuel spray and flame into said tubular member in order that combustion will take place over most of the cross sectional area thereof.

Another object of the invention is to provide an improved flame holder and fuel distributing fixture for a ram jet engine.

This invention consists of a tubular member whose forward and rearward ends are contracted and in which a fuel distributing fixture is arranged which supports a plurality of nozzles whose orifices discharge fuel outwardly toward the casing and slightly forwardly and which has a forwardly facing axially positioned nozzle provided with an orifice larger in diameter than the orifice of the first mentioned nozzle and which discharges fuel directly into the air stream entering the tubular member. The fuel distributing fixture is supported in the forward end of the tubular member by means of a flanged ring to which a plurality of circularly disposed arms are secured which also function as flame holders, one end of each arm being secured to the ring and then inclined rearwardly and outwardly until their opposite or outer ends contact the inner surface of the tubular member and are secured thereto, the arms being provided with a flat face on the rearward side and with a rib on the forward side for strengthening the arms.

In the drawings:

Fig. 1 is a longitudinal sectional view of the improved ram jet engine,

Fig. 2 is an end view thereof looking toward the left of Fig. 1 with parts broken away to show detail,

Fig. 3 is a sectional view taken along the line 3—3 of Fig. 1,

Fig. 4 is a sectional view taken substantially along the line 4—4 of Fig. 1,

Fig. 5 is a sectional view taken along the line 5—5 of Fig. 2; and

Fig. 6 is a sectional view taken along the line 6—6 of Fig. 2.

The invention is embodied in the structure set forth in the accompanying drawings in which the numeral 1 designates a longitudinally extended tubular member whose forward and rear-

ward ends are contracted to form the intake and exhaust orifices for a ram jet engine. A bracket 2 is suitably fastened to the tubular member 1 for the purpose of securing it to the 5 outward end of a rotor blade or other movable member. The forward end of the tubular member 1 is partially curled about and secured to ring 3 and a liner 4 has one end partially curled about and secured to ring 3. This liner extends rearwardly and flares outwardly into the tubular member 1 until it abuts the wall thereof where it begins to be substantially parallel to the longitudinal axis of the tubular member. The liner 4 defines a diffusing chamber in the forward end 10 of the tubular member 1.

A flanged ring 5 is arranged in the forward end of the tubular member 1 and is supported therein by a plurality of circumferentially arranged arms 6, one end of each being secured 20 to the ring. The arms 6 flare outwardly and rearwardly and the outer ends or extremities thereof are provided with tabs 7 that terminate substantially flush with the outer end of liner 4 and are in contact with the liner. The arm tabs 7 and outer end of the liner are then suitably secured to the tubular member 1 by means of rivets 8 or other suitable means.

Each of the arms 6 is preferably made up of 25 two right angle bars 9, 9. One leg of each of the angular bars is placed in abutting relation and then secured together by welding or other suitable methods so that the resulting arm has a flat face 10 on one side thereof and a rib 11 on the other. The arm is assembled so that rib 35 11 faces forwardly and the flat face 10 faces rearwardly. The rib 11 strengthens or stiffens the arm, thereby preventing its bending during operation.

The fuel distributing head or fixture 12 is arranged in the diffusing chamber just aft of the forward end of tubular member 1 and is removably secured to the flanged ring 5 by screws 13. A plurality of circumferentially arranged nozzles 14 is secured to the fuel distributing fixture 12 40 in such a manner that they discharge fuel toward the inner surface of liner 4 and the forward end of the tubular member. The axially arranged nozzle 15, secured to fixture 12, has an orifice therein that is larger than the orifices in nozzles 14. The nozzle 15 points forwardly and functions as a pilot jet for the engine and discharges fuel directly in the air stream entering the tubular member. Fuel is conducted to the distributing fixture 12, and supplied by it to the 45 nozzles 14 and 15, by means of a conduit 16 con-

nected thereto by a nipple 17 and extends rearwardly from the fixture 12 and passes through the wall of the tubular member 1 so that it may be connected to a suitable source of fuel supply. The fixture is, therefore, a fuel supply means for the nozzles. The passageways through fixture 12 may be proportioned as to size in the same manner as the orifices in each of the nozzles, if so desired.

Initial ignition of fuel introduced into the engine is accomplished by a spark plug 18 connected to a suitable ignition coil. The spark plug is mounted in a V member 19 connected between two of the arms 6, the apex of the V facing forwardly.

Initial ignition of the engine is produced by moving the tubular member 1 at a predetermined speed through the air, after which fuel is introduced to the fuel distributing fixture 12 and thence discharged through nozzles 14 and 15 into the air. Air will be moving through the intake end of the tubular member at a high rate of speed and will carry the fuel back into the combustion chamber of the engine. At lower speeds the fuel discharge from nozzle 15 will be distributed over a considerable area of the ram jet engine, but at higher speeds the discharge from nozzle 15 will flow back upon itself and be carried toward the central portion of the tubular member. The discharge from nozzles 14 will likewise be carried back into the tubular member; but since this fuel will be projected substantially radially outwardly and forwardly it will enter the outer portions of the interior of the tubular member. It is understood that initial ignition of this fuel will be accomplished by a spark plug 18 and thereafter the burning process will be continuous and the spark plug may then be disconnected from its ignition coil. The arms 6, in cooperation with the discharge from nozzles 14 and 15, contribute to obtaining optimum thrust from the fuel introduced into the tubular member. The discharge from nozzle 15 makes its contribution to the optimum output by supplying fuel to the more central portions of the engine tubular member 1, and the nozzles 14 contributing their share by providing the fuel in the areas of the tubular member outwardly from the central portion toward the interior periphery thereof. Arms 6 modify the fuel distribution over the cross-sectional area of the tubular member so that said discharge is more uniformly distributed. The arms hold the flame and, by reason of their slope, carry some of the fuel toward the interior periphery of the tubular member where combustion will take place. The slope of the arms is so chosen that maximum combustion of fuel must occur within the combustion chamber of the engine.

In further explanation of the function of the arms 6, the ribs 11 are directed forwardly into the stream of air and fuel mixing in the inlet of the tubular member 1 defined by the forward portion of the liner 4. These ribs 11, because of their shape act to divide the air and fuel mixture into two paths of flow which is laterally outwardly in the general direction of the flanges forming the face 10. It is noted that certain of the arms 6 intervene or are located between the nozzles 14 and others are aligned with the nozzles. This is to cause the intervening arms 6 to divide some of the air streams which may not carry as much fuel backward from the nozzles as other of the streams and greatly assist in mixing the air and fuel of the various streams which are directly back of the nozzles. The alternate

alignment of nozzles 14 and arms 6 is not to be taken as a limitation, but is just one arrangement which has been successfully operated. The arms 6 thereby create great turbulence of the air and fuel mixture and tend to more evenly distribute the mixture in the area surrounding the arms. Furthermore, the slope of the arms tends to hold the flame in that area and move it near the inner periphery of tubular member 1, so that the high velocity combustion (due to speed of motion of the engine and air speed) may be held or stabilized in the combustion area and flame prevented from reaching the exhaust area, thereby increasing the desired thrust effect obtained by the expansion of hot gases.

The output of the engine may be varied by replacing the distributing head 12 with one having a different number of nozzles thereon, changing the length of the head or its axial position in the tubular member, providing different size orifices in the nozzles and by changing the angle at which nozzles 14 are mounted on the head as well as by varying the slope of the arms.

What we claim is:

1. A ram jet engine comprising a tubular member open at its forward and rearward ends, and through which an air stream passes between the forward and rearward ends; a plurality of arms mounted in the forward end of said tubular member and diverging outwardly and rearwardly from a point on the longitudinal axis of said tubular member, each arm resisting air stream movement and having a trailing flat face and a ribbed forward face, the flat faces of the plurality of arms creating turbulence in the zones adjacent the arms for holding flames in the forward end of said tubular member adjacent to and on said arms; a fuel supply fixture supported by said arms near the forward end of said tubular member on the longitudinal axis thereof; and a plurality of fuel nozzles mounted on said fixture forwardly of said arms adjacent to and within the forward end of said tubular member for directing fuel forwardly of said arms into said air stream, the fuel being carried by the incoming air stream into the turbulent zones adjacent said arms and directed outwardly toward the inner periphery of the tubular member by said diverging arms for burning, the flames being held on the arms and adjacent the inner surface of said tubular member.

2. A ram jet engine comprising a tubular member through which an air stream passes between an intake and exhaust outlet, a plurality of fuel nozzles mounted in said tubular member near the inlet end for directing fuel into the air stream; a source of fuel connected with said nozzles; and means for supporting said nozzles in said tubular member which includes a plurality of outwardly and rearwardly inclined flame holder arms diverging from a point on the longitudinal axis of the tubular member and disposed rearwardly of said nozzles and each having a forwardly projecting rib on the front side and a flat surface on the rear side, the air stream with the fuel therein being swept onto said arms for burning, the edges of said arms holding the flame and the rib on each of said arms directing the flow of the air and fuel into divergent streams to create turbulence and resistance to passage.

3. A ram jet engine comprising a tubular member open at the forward and rearward ends thereof and through which an air stream is received and discharged; a fuel distributing fixture

in said tubular member; means for supplying fuel to said fixture; means for supporting said fixture in the forward end of said tubular member, said means including a plurality of arms connected to said fixture and to the inner surface of said tubular member, said arms diverging outwardly and rearwardly from said fixture, and each arm being formed with laterally extending flat rearward portions and a reinforcing rib on the forward side thereof extending into the air stream, the reinforcing ribs and flat portions of said arms directing the flow of air entering the tubular member into divergent streams to create turbulence and resistance to passage, the edges of the rearward portions constituting the flame holders for the engine; and a plurality of nozzles secured to said fixture and provided with discharge orifices, said nozzles being disposed in the forward end of said tubular member for discharging fuel into the flow of air entering ahead of said arms, the fuel being carried along by the air into said divergent streams.

4. A ram jet engine comprising a tubular member open at the forward and rearward ends thereof to admit the flow of air therethrough due to forward movement of said tubular member; a fuel supply fixture; supporting means for said fixture positioning said fixture near the forward end of said tubular member, said supporting means including radially directed arms circumferentially spaced within said tubular member and connected to said fixture and inclined relative to the longitudinal axis of said tubular member, said arms being connected with said tubular member, each arm having a rib projecting forwardly into the air stream and laterally directed flanges extending across the air stream at each side of said rib; and a plurality of fuel discharging nozzles on said fixture directing fuel into the flow of air entering at said forward end of said tubular member, said fuel mixing in said air stream and being swept rearwardly against said arms, said ribs and flanges of said arms dividing and holding the mixture of fuel and air adjacent thereto for combustion aft of said arms, the flame being held on said arms.

5. A ram jet engine comprising a tubular member open at the forward and rearward ends thereof to admit of the flow of air therethrough due to forward movement of said tubular member; a fuel supply fixture; a supporting means for said fixture positioning said fixture centrally of said tubular member near the forward open end thereof, said supporting means including a plurality of flame holder arms each connected to and extending rearwardly from said fixture and connected to said tubular member in an inclined position relative to the longitudinal axis of said tubular member, each of said arms having a rib projecting forwardly into the air stream flowing through the tubular member and each arm having laterally directed flanges; a plurality of fuel discharge nozzles on said fixture angularly disposed relative to the longitudinal axis and discharging fuel against the air stream entering at the forward end of said tubular member to be swept back toward said inclined arms and directed by said inclined arms outwardly to a location near the inner periphery of said tubular member; and an additional axially disposed fuel nozzle in said fixture discharging fuel axially forwardly into the incoming air stream to be swept back centrally of said tubular member for combustion aft of said arms, the flame being held on the arms.

6. A ram jet engine comprising a tubular member open at the forward and rearward ends thereof and through which an air stream passes; a fuel supply fixture, means for supporting said fixture in said tubular member near the forward end thereof, said supporting means including arms extending radially outwardly and being rearwardly inclined relative to the position of said fixture, each arm having laterally directed flanges defining a substantially flat rearward face and each arm having a rib facing into the air stream to divide the air, each arm creating turbulence in the area surrounding and between said arms; a fuel supply conduit connected to said fixture; and a plurality of nozzles carried by said fixture and disposed forwardly of said supporting arms, said nozzles being supplied with fuel from said fixture for discharge into the air stream to be swept rearwardly for combustion in the turbulent area aft of said arms, the flame being held on said arms.

7. A ram jet engine comprising a tubular member open at the forward and rearward ends thereof and through which an air stream passes; a fuel supply fixture; a supporting structure for said fixture locating the latter centrally of said tubular member near the forward end thereof, said structure including flame holder arms connected to said tubular member and extending in inclined relation to the longitudinal axis of said tubular member to points relatively rearwardly of said fixture, said arms being of non-streamlined cross section and creating turbulence in the area surrounding said arms rearwardly of said fixture; a plurality of nozzles circumferentially arranged on said fixture to be supplied with fuel thereby, said nozzles directing the fuel forwardly into the air stream to be swept rearwardly into said arms for burning in the turbulent area surrounding said arms; and an additional centrally located nozzle on said fixture receiving fuel therefrom and directing the fuel forwardly against the incoming air stream centrally of said tubular member to be swept back into the central part of the turbulent area of the ram jet engine, the flame being held on said arms.

8. A ram jet engine comprising a tubular member open at the forward and rearward ends thereof and through which an air stream passes due to forward movement of the engine; a fuel supply fixture; a plurality of radially directed flame holder arms having inner ends supporting said fixture near the forward end of said tubular member and along the longitudinal axis thereof, said arms being fixed at their outer ends to the inner periphery of said tubular member in a zone space rearwardly of the inner ends and said fixture relative to the direction of movement of the air stream, each of said arms having flanges projecting laterally into the air stream to create a turbulence zone and impede passage of the air past said arms; and a plurality of nozzles on said fixture supplied with fuel therefrom to be directed into the incoming air stream over the area of the forward end of said tubular member, the fuel thus directed being swept rearwardly for combustion in the turbulent zone, said flame holder arms holding the flame for burning fuel aft of said arms.

9. A ram jet engine comprising a tubular member open at the forward and rearward ends thereof and through which an air stream flows; a fuel supply fixture; a plurality of flame holder arms radially directed from the longitudinal axis of said tubular member and having their inner ends

supporting said fixture on said axis near the forward end of the tubular member and outer ends of the arms connected with the inner periphery of the tubular member, said arms having a non-streamlined cross-section and having the outer ends thereof located relatively rearwardly of the inner ends so as to locate the arms across the air stream and distribute the air flow toward the inner periphery of the tubular member; and a plurality of nozzles spaced about said fixture on the forwardly facing portion thereof, said nozzles being supplied with fuel from said fixture for delivery forwardly into the incoming air stream over the area near said forward end of the tubular member, the fuel mixing with the air and being swept rearwardly for burning in the zone aft of said flame holder arms, the flames being held on said arms.

10. A ram jet engine comprising a tubular member open at the forward and rearward ends for the flow of air therethrough due to forward movement of the engine; a fuel supply fixture near the forward end of said tubular member; supporting means for said fixture locating said fixture on the longitudinal axis of said tubular member, said support means including circumferentially spaced radially extending and rearwardly inclined arms, said arms having surfaces offering resistance to the air flowing toward the rearward end of said tubular member to hold the flame of burning fuel aft of said arms, the flames being held on the edges thereof; a plurality of nozzles on said fixture in circumferential spaced and forwardly directed locations, said nozzles directing fuel supplied from said fixture forwardly into the air stream to be swept rearwardly toward said arms; and an axially located, forwardly directed nozzle on said fixture in addition to the aforesaid nozzles and receiving fuel from the fixture and directing some of the fuel forwardly to be swept rearwardly to the more central area of said tubular member for burning aft of said arms, the flame being held on said arms.

11. A ram jet engine comprising a tubular member open at the forward and rearward ends for the flow of air therethrough due to forward movement of the engine; a fuel supply fixture in the forward end of said tubular member; supporting means for said fixture including arms connected to said fixture at the inner ends of the arms, said arms extending radially outwardly in rearwardly inclined relation to the longitudinal axis of said tubular member and having the outer ends of said arms connected with the inner periphery of said tubular member, said arms locating said fixture on the longitudinal axis of said tubular member forwardly of said arms, and each arm having a ribbed surface facing the forward end of the tubular member and opposing the flow of incoming air creating turbulent resistance to air movement in the zone surrounding and aft of all of said arms; and a plurality of nozzles on said fixture to receive fuel therefrom and to direct the fuel forwardly into the incoming air stream at the forward end of said tubular member, the fuel mixing with the air and being swept rearwardly by the incoming air into the turbulent zone surrounding and aft of said arms for burning aft thereof, the flame being held on said arms.
